CLAIM

USPC D14/485

I claim the ornamental design for a display screen with graphical user interface, as shown and described.

(58) Field of Classification Search

DESCRIPTION

USPC D14/485-488

FIG. 1 is executed in color. Copies of this patent or patent application publication with color drawing(s) will be provided by the Office upon request and payment of the necessary fee.

CPC H04M 1/724-7248; G06F 3/048; H04L 67/12; G16H 40/20

FIG. 1 is a front view of a first embodiment of display screen with graphical user interface showing the claimed design; and,

See application file for complete search history.

FIG. 2 is a front view of a second embodiment of display screen with graphical user interface showing the claimed design.

(56) References Cited

The outermost broken lines in the figures show a display screen, and form no part of the claimed design. The other broken lines in the FIGURE show portions of the graphical user interface that form no part of the claimed design.
